US0D1053220S

(12) **United States Design Patent** (10) **Patent No.:** **US D1,053,220 S**
(45) **Date of Patent:** **** Dec. 3, 2024**

(54) **IMPELLER FOR PUMPS**

(71) Applicant: **EBARA CORPORATION**, Tokyo (JP)

(72) Inventors: **Tsuyoshi Maeda**, Tokyo (JP); **Takahiro Noji**, Tokyo (JP); **Shrunali Ranade**, Tokyo (JP); **Miho Isono**, Tokyo (JP); **Tetsuya Ishiwata**, Tokyo (JP)

(73) Assignee: **EBARA CORPORATION**, Tokyo (JP)

(**) Term: **15 Years**

(21) Appl. No.: **35/519,334**

(22) Filed: **Dec. 15, 2022**

(80) **Hague Agreement Data**

Int. Filing Date: **Dec. 15, 2022**

Int. Reg. No.: **DM/229136**

Int. Reg. Date: **Dec. 15, 2022**

Int. Reg. Pub. Date: **Dec. 15, 2023**

(30) **Foreign Application Priority Data**

Jun. 24, 2022 (JP) ..... 2022-013601 D

(74) *Attorney, Agent, or Firm* — PEARNE & GORDON LLP

(57) **CLAIM**

The ornamental design for an impeller for pumps as shown and described.

DESCRIPTION

1.1 : Perspective

1.2 : Perspective

1.3 : Front

1.4 : Back

1.5 : Left

1.6 : Right

1.7 : Top

1.8 : Bottom

1.9 : Cross sectional

1.10 : Cross sectional

The article is an impeller for pumps; the feature of the design

resides in shape and configuration of the article as shown in

(Continued)

the reproductions; reproduction **1.9** is a cross-sectional view taken along the line **1.9-1.9** in reproduction **1.3**; reproduction **1.10** is a cross-sectional view taken along the line **1.10-1.10** in reproduction **1.3**.
